UNITED STATES PATENT OFFICE.

CHARLES J. VAN DEPOELE, OF CHICAGO, ILLINOIS.

COMBINED CONDUIT AND OVERHEAD SYSTEM FOR ELECTRIC RAILWAYS.

SPECIFICATION forming part of Letters Patent No. 424,380, dated March 25, 1890.

Application filed June 6, 1888. Serial No. 276,260. (No model.)

To all whom it may concern:

Be it known that I, CHARLES J. VAN DEPOELE, a citizen of the United States, residing at Chicago, in the county of Cook, State of Illinois, have invented certain new and useful Improvements in Combined Conduit and Overhead Systems for Electric-Railway Conductors, of which the following is a description.

My invention relates to improvements in means for conveying electric currents to moving motors; and it consists, partly, in the combination of a system of conductors located in an underground conduit with a system of conductors suspended above the roadway, both systems being arranged, constructed, and combined to operate in harmony and in conjunction, so that a portion of the railway may be equipped with an overhead-conductor system and another portion with an underground-conduit system; or two separate electric railways equipped with the different systems may, by means of my invention, be operated in conjunction, so that a car may pass from one line to the other and traverse both railways without inconvenience or delay. It also affords a desirable means of crossing bridges and steam-railroads.

The invention also comprises traveling contact devices for both overhead and underground systems, and means for safely disposing the contact device of the system not in use. It also includes various features of construction and arrangement hereinafter fully pointed out, and referred to in the appended claims.

In the drawings illustrating my invention, Figure 1 is a view in elevation showing a portion of an electric railway equipped with both overhead and underground systems of conductors, the point chosen for illustration being where the overhead system begins and the underground system terminates, parts of the underground conduit being shown in sectional elevation. Fig. 2 is a top plan view of the underground conduit shown in Fig. 1. Fig. 3 is a cross-section of the conduit on the line 3 3 of Fig. 2. Fig. 4 is a view in elevation showing one side of the underground conduit and the traveling contact-truck in position thereon. Fig. 5 is an end view of the conduit and contact-carriage on the line

5 5 of Fig. 4. Fig. 6 is a top plan view showing the contact-brushes in position between the conductors, the same being on the line 6 55 6 of Fig. 4. Fig. 7 is a detail view showing the means for supporting the contact-carriage when out of the conduit. Fig. 8 is a detail view showing parts of the car-frame, the devices for supporting the contact-carriage, 60 and means for releasing the carriage therefrom. Fig. 9 is an elevation similar to Fig. 1, but showing the details of the overhead contact devices, means for guiding the same into position upon the overhead conductor, a 65 modification of the contact-carriage and suspending devices, and the circuits to and from the traveling electromotor. Fig. 10 is a view in perspective showing the devices extending from the extremity of the suspended conductor for guiding the contact-arm and grooved wheel into engagement with the conductor. Fig. 11 is a detail view showing the tension-spring by which the contact-wheel is held up against the conductor. Fig. 12 is 70 75 a view in perspective showing in more complete and extended form the terminus of the suspended conductor illustrated in Fig. 10, together with a motor-car and devices for making contact with the said conductor. 80

As illustrated in the drawings, A indicates a car of any desired type. At B is shown a railway, of which b b are the rails, upon which latter the car A travels, and between which is located the conduit for the reception and protection of the main electric conductor or conductors. 85

The exposed portions of the conduit consist of metallic surface or capping plates E E, between which is formed the slot G. The precise details of the conduit structure form no part of my present invention, except so far as they relate to the removal and replacement 90 of the contact-carriage operating in connection therewith.

The structure herein shown forms part of a separate application heretofore filed by me, Serial No. 276,256, June 6, 1888, and it will be obvious that any of the various underground conduit structures shown and described in 100 my various applications for Letters Patent may be used in connection with the novel features herein presented.

The conduit is preferably in the center of

the roadway, and its structure includes continuous side walls, which, for economy of construction and also on account of its insulating properties, may be formed of wooden planks of, say, three by ten inches in dimensions, joined together at their ends in any suitable manner so as to form the continuous side walls B B of the conduit. The side walls B B are preferably supported by metallic yokes C in downwardly-divergent positions, forming an inverted V, as seen in cross-section, and having their upper edges separated to form a continuous slot G. The yokes C are made large enough to receive the side walls and to constitute sufficiently strong and substantial supports therefor. The yokes C are formed with flanges C' extending around their inner margins, upon which flanges the lower edges of the side walls rest, and against which said side walls are securely fastened by means of suitable bolts C², the said side walls being thus maintained at the desired distance apart by the yokes, which are placed at suitable intervals along the conduit, ordinarily four feet apart.

The electrical conductors D, which may consist of bars or rods of iron or steel faced with copper, or bars of pure copper, are supported within the conduit upon cleats d d, secured to the side walls B, and by which said conductors are kept from contact with the said side walls and supported at a convenient height in position intermediate between the bottom and top of the conduit. When both are connected to form one side of the circuit, the conductors D are electrically connected at intervals, so that in case of accident to one conductor the current will pass around the break to the remaining conductor and the flow of the current not be materially interfered with.

The upper edges of the side walls B B are covered by capping-plates E E, which may be in the form of flat iron or steel bands or bars secured along the surface of the outer edges of the conduit, their upper surfaces being about on a level with the surface of the roadway. The plates E are secured in position by lag-screws e or other suitable means. A continuous opening or slot G of, say, five-eighths of an inch in width is left between the inner edges of the capping-plates for the passage of a portion of a contact-truck carrying the contact devices operating upon the interior conductors.

Devices for establishing and maintaining a traveling contact with the main conductors D within the conduit may be constructed in many different ways without reference to other features of my invention, various forms thereof being shown, described, and claimed in contemporaneous applications for Letters Patent. (See Patents No. 403,009, May 7, 1889, No. 403,800, May 21, 1889, and No. 405,626, June 18, 1889.)

As herein illustrated, such devices consist of a number of thin plates or leaves of copper H, or other metal of good conductivity,

substantially rectangular in shape and of a width slightly exceeding that of the main conductors D and somewhat longer than the distance between said conductors. A number of the plates H are secured between strong metallic end pieces L by bolts h, passing longitudinally through the plates and through or into said end pieces L. The plates H are each separated by suitable washers h' to allow for the greatest amount of flexibility, and all of the plates H, together with their supporting-bolts h', are insulated from their supports L. A conducting-strip H' is electrically connected with any desired number of the plates H, and extends upward therefrom between the end supports L, and is connected at its outer extremity to a suitable conductor J, extending to the traveling motor. The conducting-strip H' is inclosed between protective plates I I, of insulating material, upon the exterior of which are secured protective plates K K, of steel or other durable material. The protective plates fit in between the end supports L L, so as to constitute a strong and durable supporting device for the interior contacts. Metallic arms k k are secured on the exterior of the protective plates K a short distance above the interior contact plates or brushes H. The arms k k project beyond both end supports L, and their extremities are connected to the axes of and carry wheels or rollers i. The peripheries of the wheels i extend slightly below the contact-plates h, and the wheels themselves, being comparatively small and thin, are carried between the main conductors, one at each end of the contact device, but entirely out of electrical contact therewith.

As an alternative construction for the auxiliary carrying-rollers i, the arms K may be prolonged and turned up at their extremities to form shoes, taking the place of the said wheels i, as shown in Fig. 9.

The interior contact devices just described are when in operation supported at the desired height within the conduit by metallic wheels M, which rest and travel upon the capping-plates E. The supporting-wheels are or may be provided with flanges or ribs M', to move in the slot G, keeping the wheels in place. The wheels M are pivotally attached to the end pieces L by means of strong metallic brackets m, bifurcated at their outer extremities for connection with the axles n of the said wheels. The ends of the lower portions or members of the brackets m are let into slots or recesses l, formed for their reception in each of the end pieces L, the upper portions of brackets fitting over a stout frame-piece O, extending about and desirably resting upon the upper portion and edges of the end pieces L and protective plates K. The brackets and frame-pieces are all securely connected by pivot-bolts O', which extend through both limbs of each bracket, opposite ends of the frame O, and into the end pieces L, affording a strong and vertically-rigid sup-

port for the contact devices upon its carrying-wheels M. The several parts designated form a strong and serviceable composite device, hereinafter referred to as a "contact-truck." The plate O is provided with upward-extending lugs k', and the plates K with pins k², to which or other convenient fixed points on the contact-truck are pivotally attached parallel looped or double connecting-
10 rods Q Q, hinged at their outer extremities q q to a beam Q' underneath the car. The parallel rods Q Q allow of free vertical movement between the car and contact-truck, but prevent the latter from plunging or upsetting.
15 A suitable arrow-headed or other shaped catch j is also secured to the lugs k' of the plate O.

A pair of spring-jaws R R, pressed together through their own resiliency or by suitable
20 springs R', are suitably pivoted to the under side of the car in the vertical path of the contact-truck. The jaws R are further provided with divergent guiding-extensions R², and when the contact-truck is lifted high enough
25 above the conduit the spring-jaws R will engage the catch j and the contact-truck be suspended above the surface of the roadway when not in use. A wedge-shaped block r is located between the spring-jaws R and connected to a suitable hand-lever R³ by a connecting-rod v'. When the wedge r is drawn between the jaws by appropriate movement of the hand-lever, it will separate said jaws and release the carriage.
30

35 At the termination of the underground conduit inclined planes are provided, over which the contact-truck passes, and is thereby automatically raised out of the conduit and caused to engage its suspending devices.

40 Starting from near the bottom and at a short distance from the termination of the conduit is an inclined plane or track, consisting preferably of a flat metallic bar A², said bar being supported upon braces a, secured
45 to the side walls B, and rising gradually to a point where the auxiliary wheels i will rest thereon. (See Fig. 4.) The capping-plates do not extend beyond the ends of the conductors D, and the remaining short section of conduit
50 beyond their ends is closed by a hinged cover A³, provided at its under side with an arched backing a². The truck A² rises upward from the ends of the conductors D to the hinge of the cover A³, and when the said cover is thrown back upon its hinge, as indicated in the drawings, a continuous inclined way is formed, along which the wheels i i of the contact-carriage travel as the car moves beyond the end of the conduit, the contact-truck rising gradually with the grade and issuing from the conduit through the opening made by the removal of the cover A³, passing thence over said cover, the elevation on the under side of which is so proportioned that when passing
55 over its apex the spring-jaws will automatically engage the catch on the carriage. On re-entering the conduit the hand-lever is actuated

while the carriage is passing over the arch a', from which point it will gradually descend into the conduit and resume its place 70 between the conductors D. The resiliency of the plates H will cause them to bend rearwardly, and so make a continuous spring-contact against the inner sides of said conductors in whichever direction the carriage 75 may be moved into position between them.

As shown in Fig. 9, a rope or chain R⁴ is secured to the upper part of the contact-truck, passing over rollers r² r³ to a point within reach of the attendant. The extremity of the rope R⁴ 80 is provided with an end piece r⁴, having a projection or other means for engaging a series of points or holes r⁵. As the carriage is lifted when passing out of the conduit, the attendant will secure it in its highest position by 85 the means described, instead of the carriage being automatically secured between the spring-jaws R. Similarly on the return the end piece r⁴ will be disengaged instead of the jaws R, being distended by the wedge r.
90

Beginning at a point a short distance from either or both ends of the conduit, a conductor D' is suspended above the track in order that electrical connection may be established therewith prior to the severance of such 95 connection with the conduit system.

Upon a suitable post S, mounted on top of the motor-car, is pivoted a contact-arm s, the outer end of which is spring-pressed in an upward direction by suitable springs S', of 100 which there may be a plurality, secured to an arm extending from the post S, as indicated at S', Fig. 9; or the spring may be attached at or near the lower extremity of the contact-arm, as at S², and connected to a vertically-movable weight S.
105

In order to lower the outer extremity of the contact-arm s, Fig. 1, the weight S³ may be raised and held in suspended position by an insertible stop V', or other convenient 110 means. Without some provision for lowering the extremity of the arm s when not in engagement with the conductor D', it would be pulled into an almost vertical position by the weight S³; but when the weight itself is supported the outer end of the arm can be sustained at any desired height above the car, so as to be easily guided to the extremity of the suspended conductor, after becoming engaged with which the support V' can be withdrawn from under the weight S³. The conductor D' terminates in a box T, to which it is securely attached. The outer end of the box T is expanded and formed with flaring sides and top t'. The box T is preferably 115 supported from a cross-wire, as T², in any convenient manner, and from the inner sides of its flaring extremities extend guide wires or rods T', secured to posts w', located on either side of the track, or in any other convenient manner. The advantage of this construction is that the guide-wires T' and the cross suspension-wires co-operate to give both 120 the guiding-box and the conductor attached
125
130

thereto a yielding or cushioned suspension arising from the resiliency of the transverse wires and to a certain extent of the posts to which they are attached. This is of great importance when an upwardly-pressing trolley is employed, as in the present case, for any upward blow of the trolley against the conductor or the wires is taken up by the resiliency of the system and no injury results either to the insulators, the wires, or the trolley.

I am aware that upwardly-pressing trolleys have been employed with transverse brackets or similar devices for supporting the line-conductors; but in such cases it has been customary to hang the conductor by a flexible strap or spring, so that the impact of the trolley on the conductor would not be transmitted to the conductor-support, but would be taken up by the intermediate strap or spring. Such devices, however, have an uncertain alignment of the conductor, give difficulty on curves, and are open to many objections, which are obviated by my construction, in which the conductor is attached to the transverse wires substantially without intervening springs and reliance placed principally on the transverse wires for a yielding or cushioned suspension. It will also be obvious that the diagonal wires T' also serve to resist the tension of line-conductor D', and, being longer than direct transverse wires, have a greater resiliency.

The contact-arm *s* carries a suitable grooved wheel U at its outer extremity, said wheel being of a width adapted to pass through the narrowest portion of the box T, and thence along the under side of the conductor D'.

By way of illustration I have in Fig. 12 shown a more complete organization of the above-described construction. In said figure the box T is sustained partly by the guide wires or rods T' and partly by a cross-wire T², extending from the posts W' W'. To avoid the necessity for a second set of posts in the immediate vicinity of the posts W', I provide supporting-wires, which extend between the posts W' W' and the next regular cross-wire, supporting posts W² W², the cross-wire T², which is secured to the box T, being attached at its extremities and sustained by the said longitudinal wires t² t³. After leaving the box T the conductor D' is sustained in a similar manner by cross-wires T² at suitable points along its entire length, or as far as it is desired to employ this system of suspension, the resilient effect of such suspension being thereby secured whenever desired. The swaying of the car will act to swing the contact-arm *s* from side to side when approaching the suspended conductor. Said arm will, however, pass between the guides T', and be thereby directed into and then pass through the box T and into position against the under side of the conductor.

As indicated in Fig. 9, the lower extremity of the contact-arm is provided with a well-insulated hand-lever *u*, further protected by a

conical insulator *u'* at its point of connection with the contact-arm, in order to prevent streams of water and the current passing into and charging said hand-lever during wet weather. A pin or stop V projects from the car in the path of the hand-lever *u*, and in case the contact-wheel U should become disengaged from its conductor the motor-man can readily replace it by pressing up the lower end of the contact-lever and turning the same upon its pivot until the contact-wheel is again in position. The end piece *u* is also provided with notches or apertures *u*², adapted to register with the pin V, and when it is desirable to permanently lower the outer end of the contact-arm the end piece U can be pushed upward and hooked upon said pin, thereby holding the outer extremity of the contact-arm in any desired position when not in use.

A suitable switch is provided for making proper contact with either the suspended or conduit systems of conductors. The terminal W is connected by conductor 1 with the base 90 of the springs S', or other portions of the contact-arm, and is in electrical contact with the suspended conductor. A terminal Y is connected by conductor 2 with the conducting-plates H of the contact-truck, and thus represents the underground system of conductors. Z is a switch-lever connected to the positive binding-post of the motor by conductor 3. The switch Z, being pivoted between the terminals W and Y, can readily be placed upon the one representing the circuit from which it is desired to supply the motor.

From the negative binding-post N extends a conductor 4, connected to the axle of one of the carrying-wheels of the car, and an additional conductor 5 is in metallic connection with the supporting-wheels M of the contact-truck. At the point where the conduit terminates it is connected with the rails of the track by conductor or conductors 6, and the rails themselves are also electrically connected to form a return-circuit.

On that portion of the roadway provided with an underground conduit such as described the difficulty and expense of connecting the rails will be entirely unnecessary.

The suspended conductor D' is connected with the conductors D within the conduit by a wire 7, shown in Fig. 1 as attached to a conveniently-located post W'.

While describing the construction in detail for the purposes of this specification, I do not limit myself to the specific details shown and described.

In regard to the overhead contact device I desire it to be distinctly understood that in certain pending applications for patent I have made claim broadly to the form herein shown and described, and that this application is designed to cover an upwardly-pressing contact device of any suitable construction when used with a suspended conductor which has a yielding support by means of the transverse wires; that it is also designed to cover the specific

improvements in contact devices of this kind which are hereinafter claimed, and that all other features of the said contact device are reserved and claimed broadly in the said pending

5 applications, filed, respectively, March 12, 1887, No. 230,649, and June 18, 1888, No. 277,425.

Certain of the matters shown in Fig. 9 of the drawings are not herein claimed, having 10 been made the subject of a divisional application filed January 31, 1890, Serial No. 338,736.

Having described my invention, what I claim, and desire to secure by Letters Patent, is—

15 1. An electric-railway system comprising an underground conduit extending along a portion of the line of way, a vertically-movable contact-making device therefor, and an inclined plane at the terminus of the conduit 20 for automatically ejecting the contact device, substantially as described.

2. An electric-railway system having a portion of its supply-conductor arranged in a conduit, and a portion thereof suspended directly 25 above the line of way and above a vehicle traveling thereon, a vertically-movable contact-truck arranged to travel in the conduit in engagement with the conductor or conductors therein, a contact device extending upward 30 from the roof of the vehicle to engage the suspended conductor, and means, comprising an inclined way, for automatically throwing the contact-truck out of operative relation with the underground conductors when the 35 aerial-contact reaches an operative position.

3. An electric-railway system comprising both underground and suspended conductors, a vertically-movable traveling contact-truck for the underground portion, and an aerial contact-making device for the overhead portion, and an inclined plane at the terminus of the 40 underground portion for ejecting the contact-truck when the aerial contact is in position to engage the suspended conductor, substantially as described.

4. An electric - railway system comprising conductors located in an underground conduit and extending along a portion of the line of railway, a vertically-movable traveling 45 contact device therefor, and a continuing system of suspended conductors, and means, substantially as described, for establishing a moving contact therewith, substantially as described.

5. In an electric railway, the combination, with a conduit between the tracks, of a traveling contact device thereon connected to move with the motor-car, an inclined way or track at the termination of said conduit, and 50 means for securing the contact-truck to the under side of the car on reaching the summit of said inclined track, substantially as described.

6. In an electric railway, the combination 55 of a suspended conductor, a moving vehicle, a contact-carrying arm extending upward from the vehicle, and guides converging to-

ward the end of the conductor and adapted to automatically direct the contact to its operative position in relation thereto, substantially as described.

7. An electric - railway system comprising the combination of an underground conduit extending along a portion of the line of railway, main conductors located therein, a continuing suspended conductor, electrical connections between the suspended and underground conductors and between the return-circuit of the conduit and the rails, and means, consisting of an upward contact-arm, 75 for establishing connection between the suspended conductor and the motor-car, guides extending from the suspended conductor for directing the contact-arm into operative position, and a contact - truck for contact between the inclosed conductors and the car, 80 substantially as described.

8. An electric - railway system comprising conductors located in an underground conduit and extending along a portion of the 90 line of railway, and a continuing system of conductors suspended over the remainder thereof, a traveling contact moving in the conduit, and inclined planes for automatically ejecting the contact device at the terminus of the conduit portion, an upwardly-extending contact-carrying arm, and converging guides for automatically directing the contact-arm toward the suspended conductor, 95 substantially as described.

9. An electric - railway system comprising the combination of an underground conduit and a suspended conductor, electrical connections between the suspended and underground conductors and between the return-circuit of the conduit system and the track-rails, a contact-arm and a contact-truck for contact, respectively, with the suspended and underground conductors, a return-circuit including both the conduit and the track-rails, 105 circuit-connections from the two main conductors, and a switch for connecting the motor with the desired source of supply, substantially as described.

10. In an electric railway, the combination, 115 with a suspended conductor, of branching guide rods or wires and flaring guide-boxes at the extremities of said rods or wires, and the main conductors secured to the inner extremity of the boxes, substantially as described.

11. In electric railways, the combination of the motor-car, an upward-extending contact device thereon, converging guides, a flaring box, to the outer edges of which the guides 125 are attached, and the main conductor secured to the smaller extremity of the box, whereby the contact device is automatically guided to position against the under side of the suspended conductor, substantially as described.

12. In electric railways, the combination of a moving vehicle, a suspended conductor, a contact-arm extending upwardly from the top of the vehicle and provided with a downward-

ly-extending hand-lever at or near its lower extremity, and stops arranged to engage the said lever to hold the contact-arm in any desired position, substantially as described.

5. 13. A traveling contact-truck for electric railways, comprising exterior supports, contact devices extending into the interior of the conduit, auxiliary supporting devices within the conduit, and an inclined plane within the conduit for engaging the auxiliary supporting devices to elevate the contact-truck, substantially as described.

14. In electric railways, the combination of a conduit for electric conductors, located along the line of travel of the vehicle, suspending devices at the under side of the vehicle, a contact-truck comprising exterior supports adapted to move along the exposed portions of the conduit, and a contact device extending into the interior thereof, an inclined way at the terminus of the conduit, and supplemental supporting devices arranged to travel upon and elevate the contact-truck on reaching the terminus of the conduit and to automatically bring said truck into contact with its suspending devices, substantially as described.

15. In electric railways, the combination of a system of inclosed conductors, an inclined track or way for automatically removing the contact-truck from the conduit at the terminus thereof, and a suspended conductor provided at its extremity with an outwardly-flaring guide box or frame, and guide-arms diverging therefrom, and an upwardly-spring-pressed contact-arm moving with the vehicle, substantially as described.

16. In electric railways, the combination of the conduit having an inclined track or way at its extremity, a contact-truck having a notched head or hook, a pair of spring-jaws mounted against the under side of the car and formed with downwardly-diverging guides, and a wedge-block arranged between the upper portions of the spring-jaws, and mechanical connections extending to the vehicle for moving said wedge longitudinally to liberate the contact-truck, substantially as described.

17. In an electric railway, the combination, with a suspended conductor, of a vehicle having an upwardly-pressing contact device, and transverse tension-wires attached to the conductor and giving thereto a yielding support.

18. In an electric railway, the combination,

with a suspended conductor, of a vehicle having an upwardly-pressing contact device, and transverse tension-wires extending from the conductor to posts upon opposite sides of the railway and giving to the conductor a yielding support.

19. In an electric railway, the combination, with a suspended conductor, of a vehicle having an upwardly-pressing contact device, a guide for said contact device attached to the conductor, and transverse wires giving the guide and the conductor a yielding support.

20. In an electric railway, the combination, with a suspended conductor, of a vehicle having an upwardly-pressing contact device, and supporting devices for the conductor giving it a yielding suspension, and consisting of diagonal tension-wires extending to posts at the side of the railway.

21. In an electric railway, the combination, with a suspended conductor, of a vehicle having an upwardly-pressing contact device, a guide for the contact device attached to the conductor, and transverse wires extending from the guide to opposite sides of the street.

22. In an electric railway, the combination, with a suspended conductor, of a vehicle having an upwardly-pressing contact device consisting of a lever-arm having a contact-wheel journaled in its outer end, and transverse wires extending from the said conductor to the sides of the railway, whereby it has a yielding support.

23. In an electric railway, the combination, with suspended conductor D', of a guiding-box for the contact device, having a yielding suspension by means of side posts and transverse wires.

24. In an electric railway, the combination, with a suspended conductor, of a vehicle having a contact-carrying rod or arm extending to the suspended conductor, a tension-spring engaging the lower portion of said arm for imparting upward movement to its outer end, a weight connected with said spring for placing the same under tension, and a removable support for sustaining the weight when said contact-arm is not in use.

In testimony whereof I hereto affix my signature in presence of two witnesses.

CHARLES J. VAN DEPOELE.
